UNITED STATES PATENT OFFICE.

PATRICK J. HORGAN, OF BEVERLY, MASSACHUSETTS, ASSIGNOR TO UNITED SHOE MACHINERY CORPORATION, OF PATERSON, NEW JERSEY, A CORPORATION OF NEW JERSEY.

PRESS.

Application filed August 6, 1924. Serial No. 730,461.

This invention relates to clicking machines. The invention is illustrated as embodied in a machine of the type set forth in United States Letters Patent No. 921,503, granted May 11, 1909, on application of Arthur Bates.

Clicking machines of this well-known commercial type comprise a cutting block to support shoe upper leather or other sheet material, and a presser member having a pressure-applying surface of much less area than the area of the cutting block and arranged to be swung laterally over the block into and out of co-operative relation to a die 10 freely movable and positioned by the operator as desired relatively to the material to be cut. Initially the presser member is positioned at one side of the cutting block to uncover all or the greater part of its surface to facilitate arranging the upper leather or other material to be operated upon on the block and to permit inspection of the material and the positioning of the die upon it. After the sheet material to be cut has been 20 arranged on the block and the die has been located by the operator in the desired position, the operator grasps a handle on the presser member and swings it over the die. The machine is then operated to force the 25 die through the material to cut a blank from it.

The effort required to swing the presser member by hand has made very considerable demands on the strength of the operator. 30 The presser member of a clicking machine of the type referred to must be long enough to operate upon a die positioned anywhere on the cutting block, and the cutting block must be large enough to support suitably 35 skins of upper leather as well as other sheets of material of considerable area. The width dimension of the presser member must be such that the presser member will operate effectively upon dies of considerable size, 40 such as dies for cutting out the larger shoe upper parts. To provide sufficient rigidity so that dies positioned to be operated upon by the extreme end of the presser member will be forced properly through material, the 45 presser member must be relatively deep. Consequently, the iron presser members with which clicking machines have heretofore been provided have been necessarily relatively heavy, and the labor required to over- 50 come the inertia of such a presser member

in starting it and in swinging it over the cutting block and to overcome its momentum to stop it in proper relation to the die repeatedly throughout a work day has been arduous.

It has long been recognized that it is undesirable that so much labor be required of the operator of a clicking machine, because it is very important that the operator devote his attention primarily and give his best efforts to arranging the material on the cutting block and to planning the cutting of the material. As is well known, it is especially important in the cutting of shoe upper leather to plan the cuts to obtain the best possible values from a given skin and to minimize waste. Different skins vary greatly in respect to such characteristics as stretchiness, grain and color and in respect to blemishes of various kinds. Great care must be taken, therefore, to plan the cutting of any piece of upper leather so that its various parts will be utilized for the cutting of shoe part blanks for which they are best adapted. Moreover, the various shoe upper parts are of irregular and widely differing shapes. Since upper leather is expensive, every effort must be made to avoid unnecessary waste. All this requires careful and intelligent planning. The fatigue heretofore caused by the physical effort required to move the presser member of a clicking machine laterally over the bed into and out of operative relation to the die has impaired the efficiency of the operator and has interfered with his giving his best efforts to inspecting and planning his work.

A large number of developments designed to reduce the manual labor required of the operator, and his consequent distraction and fatigue, have been proposed. Machines have been built in this country and abroad embodying power mechanisms of various types for swinging the presser member laterally over the cutting block into and out of operative relation to a die on the block. While these mechanisms lessened the physical effort required of the operator, they were more or less complicated, greatly increasing the cost of the machine, they made its operation considerably slower, thereby decreasing its output, and none of them proved commercially acceptable.

In view of the foregoing considerations, it is an object of this invention to minimize

- the energy which it is necessary for the operator to exert in starting the presser member of a clicking machine, swinging it laterally over the cutting block, and stopping it in the desired position relatively to a die positioned on the work, while retaining all the characteristic advantages which have made clicking machines of the type above referred to so successful.
- 10 This is accomplished by the present invention by the provision of a clicking machine organization in which the presser member has a density very much less than that of any presser member heretofore proposed, and yet is sufficiently hard and rigid. The illustrated clicking machine is provided with a presser member of an aluminum alloy having a high aluminum content and a correspondingly low density. Thus the 15 inertia and momentum of the presser member and therefore the labor required of the operator in starting and stopping the presser member and in moving it over the block are minimized.
- 20 Although the illustrated presser member has a weight substantially less than half that of a cast iron member of like dimensions, such as heretofore employed, nevertheless it resists satisfactorily the bending strains to which it is subjected when its 25 free end portion is operating on a die and withstands the battering of the presser member against the dies without damage either to the presser member as a whole or to its striking surface.
- 25 The operation of a clicking machine so organized requires little manual labor on the part of the operator in starting the lateral movement of the presser member, in 30 swinging it over the cutting block, or in stopping it in proper location over the die. Consequently, inspection and planning of the work are facilitated. Moreover, since the 35 operation of the machine is much less fatiguing than that of clicking machines as heretofore constructed and since the ease of operation of the presser member naturally results in more rapid swinging of that member than heretofore the production of the 40 machine is increased. The increase in output over present commercial machines of the type above referred to has been found to be from ten per cent to as much as twenty or thirty per cent, depending upon conditions. Indeed, the ease of operation is such that it is practicable for women to operate clicking machines constructed in accordance with the present invention, while heretofore the labor of swinging and stopping 45 the cast iron presser members has practically limited the operation of clicking machines to men.
- 50 A further advantage resulting from the present invention is conspicuously apparent in the cutting of fabrics, particularly in the cutting of piles each comprising a substantial number of layers of fabric. In operating upon such piles of fabric, it is especially important that the swinging of the presser member be terminated before it strikes the die to avoid producing a slanting cut through the layers of fabric and thus causing either the production of imperfect blanks or excessive waste. In the use of 55 clicking machines constructed in accordance with the present invention, so little effort is required to check the momentum of the presser member that no difficulty is experienced in stopping its swinging movement before the initiation of a pressure-applying operation of the machine, and the likelihood of moving the die laterally during the cutting is practically eliminated. Even if the operator is careless and the 60 presser member is not brought absolutely to a stop before the cutting takes place, the die, because of the smaller momentum of the presser member, will have only a small fraction of the sidewise movement which occurs in the use of machines having cast iron 65 presser members, and the slant imparted to the cut will be negligible.
- 70 Considered from another standpoint, the reduction in the inertia and momentum of the presser member of the illustrated clicking machine, as compared with the heavy iron presser members heretofore used, produces a more uniform operation of the machine with attendant advantages. The vibration of the machine is lessened so that 75 it may be used on factory floors not suitable for clicking machines as heretofore constructed; there is less wear and tear of the machine, largely due to its lessened vibration; and it operates with less noise.
- 80 Fig. 1 illustrates in side elevation and partly in section a clicking machine embodying the invention; and
- 85 Fig. 2 is a top plan view showing the cutting block and the presser member of the illustrated machine.
- 90 The invention is herein disclosed as embodied in a clicking machine of the type illustrated in the above-mentioned United States Letters Patent No. 921,503, to which 95 reference may be had for a detailed description of the construction and arrangement of parts of the machine not fully described herein. Accordingly, the illustrated machine is provided with a presser member 18 secured to a post 20 suitably journaled in a C-shaped frame member 22 so that the presser member 18 may be swung transversely above a cutting block 24 upon which is placed the material to be cut. The presser members of such machines have, prior to 100 this invention, consisted of iron castings, and since such a presser member must be long enough to reach a die placed anywhere upon the cutting block, wide enough to en-

gage effectively dies for cutting the larger shoe upper parts, and deep enough to give it the stiffness necessary to cause it to stand up under the severe pounding to which it is subjected, it has been very heavy.

The presser member 18 of the illustrated machine is composed of an aluminum alloy, indicated conventionally by the numeral 25 (Fig. 1), which is sufficiently rigid to insure that a die placed under the outer end of the presser member will be operated on substantially as effectively as a die placed near the post 20, and hard enough so that its striking face will be maintained substantially smooth and unscarred as well as free from distortion under the hammering to which it is subjected in impinging repeatedly upon the dies.

The alloy of this presser member has a high aluminum content and a correspondingly low density, the presser member thus weighing less than half as much as a cast iron presser member of like dimensions such as has heretofore been used. This minimizes the effort required in starting and stopping the presser member and in moving it laterally over the block. The operator is required, for example, to expend only about six foot-pounds of energy to produce such a swinging movement of the presser member laterally over the cutting block as heretofore required the expenditure of ten or eleven foot-pounds. It may be noted that the decrease in the energy necessary to swing the beam is almost proportional to the decrease in the weight of the beam, the discrepancy being due to the loss of energy used to overcome friction, which is approximately the same in the new and the old machines.

Satisfactory formulas for the alloy of the presser member are the following:

(a) 94% aluminum; 4% copper; 1% nickel; .5% manganese; and .5% magnesium.

(b) 89.05% aluminum; 7% zinc; 2.75% copper; 1.2% iron.

It will be understood, however, that variations may be made in the above formulas within the scope of the invention.

For reciprocating the presser member 18 to cause it to force a die 26 through material to be cut, the illustrated machine is provided with power means such as are disclosed in the United States Letters Patent referred to, this power means including a one-revolution clutch controlled from a trip handle 28 mounted upon the presser member 18, and gearing arranged, when the clutch is rendered operative, to cause a longitudinal reciprocation of post 20 and a corresponding reciprocation of presser member 18.

In the operation of the machine, the presser member 18 is swung to one side, leaving all or the greater part of the surface of the cutting block 4 exposed. The sheet ma-

terial to be operated upon, for example, upper leather or fabric, is arranged upon the cutting block. In the case of upper leather particularly, the material is carefully inspected in order to plan the cutting to the best advantage, both to minimize waste and to cut the different shoe parts from the portions of the skin which may be used to the best advantage for the several parts. A die 26 is then placed in the desired position on the material to be cut, the presser member 18 is swung by the operator into position over the die, and the machine is tripped by a downward movement of the handle 26. The pressure-applying operation is thus initiated so that the presser member 18 descends upon the die, forcing it through the material to be cut, and then returns to its raised position. After this the operator swings the presser member laterally to one side of the block for the removal of the cut blank and the repositioning of the same die or the positioning of another die on the material.

It will thus be apparent that it is necessary for the operator to swing the presser member back and forth above the block at very frequent intervals throughout the day. The effort involved, which has heretofore been burdensome on account of the weight of the presser member, is reduced, in the case of the machine of the present invention, to such an extent that little labor is required to start the lateral movement of the presser member, swing it over the cutting block, or check its momentum to stop it over the die. The operator naturally swings the lighter presser member more rapidly, at the same time conserving his energy so that he is free to give his best efforts to arranging the shoe upper leather or other material to be cut on the cutting block, to inspecting it and to planning the cutting of the material. The greater ease of operation of the improved machine results in an increase in the quantity of blanks cut, amounting to from ten to as much as thirty per cent over the daily production figures for clicking machines as heretofore constructed. Thus the ease of operation and increase of output resulting from the present invention are of such a magnitude that, from the practical standpoint, the invention constitutes a remarkable advance.

A further advantage conspicuous in the cutting of piles each comprising a substantial number of layers of fabric is that, by reason of the great reduction in the inertia and momentum of the presser member, the operator may readily stop the swinging movement of the presser member before its pressure-applying operation, so that the likelihood of the presser member striking the die while it is still moving laterally, and thereby producing a slanting cut, is prac-

tically eliminated. Even if the operator through carelessness fails to stop the swinging movement of the presser member absolutely before it strikes the die, the sidewise movement of the die will be so much less for any given speed than in the use of clicking machines as constructed heretofore, due to the greatly decreased momentum of the presser member, that the slant imparted to the cut will be negligible. This avoids the production of imperfect blanks such as have heretofore been found likely to result, particularly if the cutting edge of the die, as the result of a slanting cut, intersected the edge of the lowermost layers of the fabric. At the same time, the practical elimination of sidewise movement of the die reduces waste such as occurred when the die moved sidewise in a direction away from the adjacent edge of the fabric and thereby produced unnecessary waste between adjacent piles of blanks.

Having thus described my invention, what I claim as new and desire to secure by Letters Patent of the United States is:—

1. In a clicking machine, the combination with a cutting block of a presser member movable by hand laterally over the block to position it over a die placed in any selected position on sheet material supported on the block and also movable toward and from the die, said presser member being composed of an aluminum alloy having a hardness approximating that of iron and accordingly adapted to resist the wear to which it is subjected and having a relatively low density whereby the presser member has a relatively small inertia and momentum, to minimize the effort required of the operator in starting and stopping the presser member and in moving it laterally over the block, and power means for reciprocating the presser member

toward and from the die to force the die through the sheet material supported on the cutting block.

2. In a clicking machine the combination of a cutting block, a presser member movable by hand laterally over the block to position it over a die placed in any selected position on sheet material supported by the block and also movable toward and from the die, said presser member being composed of an aluminum alloy having a high aluminum content and correspondingly low density to minimize the inertia and momentum of the presser member and thereby to minimize the labor required of the operator in starting and stopping the presser member and in moving it laterally over the block, and means for reciprocating the presser member toward and from the die to force the die through the sheet material on the cutting block.

3. A presser member for clicking machines composed of an aluminum alloy having a high aluminum content.

4. A presser member for clicking machines composed of a copper and zinc alloy of aluminum having from 85% to 95% of aluminum.

5. A clicking machine having a mechanically reciprocated presser member arranged to be swung manually transversely of the direction of pressure, characterized by the fact that the swinging presser member is composed of a hard alloy having a high percentage of aluminum, the density of which is considerably less than that of iron, to minimize both the inertia and the momentum of the transversely swinging presser member.

In testimony whereof I have signed my name to this specification.

PATRICK J. HORGAN.
